United States Patent Office

Des. 188,506
Patented Aug. 2, 1960

188,506

HOSPITAL BED LIGHT UNIT

Mitchell Bobrick, Pacific Palisades, Calif., assignor to
Sunbeam Lighting Company, Los Angeles, Calif., a
firm

Filed May 7, 1959, Ser. No. 55,815

Term of patent 14 years

(Cl. D48—20)

FIG. 1.

FIG. 2.

FIG. 3.

FIG. 4.

FIG. 5.

FIG. 6.

Fig. 1 is a front elevation of a hospital bed light unit, showing my new design;

Fig. 2 is a top plan view thereof;

Fig. 3 is an end elevational view thereof as seen from the left of Fig. 1;

Fig. 4 is an end elevational view thereof as seen from the right of Fig. 1;

Fig. 5 is a perspective view thereof as seen from the bottom of Fig. 6 with the spotlight arms in an extended alternate position; and

Fig. 6 is a perspective view thereof as viewed from the top right of Fig. 5.

I claim:

The ornamental design for a hospital bed light unit, as shown.
